Letters Patent

"The Schedule annexed to these Letters Patent and make part of the same containing a description in the words of David Mull the right holder of his 'Regulated Wind Mill'."

The invention of this improvement called the Regulated Wind Mill, consists in constructing the arms of the Windmill on which the wind sails are put, in such a manner to have the mill regulated itself, so that let the wind hard or gently blow, the Mill will go steady and regular. To effect this, the four arms on which the sails are placed leaving the greatest half of said sails to the windward of said arms, are made of round iron or hard wood & filled with boxes on the reverse arms, so as to turn about the round, by which means the angle of the wind sails is lessened in proportion to the increasing strength of the wind, and as said angle lessens, the less the wind effecteth the said sails, the round arms center at the staff of the wind wheel, and the ends of them, from short arms, at right angles with the said other parts of them. The main staff of the wind wheel is bored through, & the hole is admitted an iron shaft, called the center shaft. On the outer end of this iron center shaft is permanently fixed the horns, made of iron. These horns are placed close at the center at right angles, and are welded together. The ends of said horns go into the ends of said short arms, and when said horns and the short arms of said round arms are admitted the said iron shaft, and close up to the end of the wind wheel staff, which being horizontally the said sails will be then turned horizontally the said sails will be then turned always to the wind, and the wind wheel will then stop. To turn the said sails to the wind so as to have the wheel turn by it, a lever is fixed at the inner end of said iron center shaft, by which said shaft (on the outer end of which said horns are fixed) is drawn and ways so as to carry said horns out, and by these means to turn the sails to a proper angle with the wind. with this said lever is contrived proper weights to contain a sufficient weight which constantly presses said center iron shaft outward so as to keep the said sails in a proper angle with the wind, in order to have the mill go as fast as may be wanted. If the wind blows harder, the said weight upon these angle by forcing inward said horns and center shaft, which operation raises said weight and the mill thereby goes regular. When the wind blows moderately but not hard enough to raise said weight, the said sail will then be kept at the greatest angle to the wind by said weight, so that by this improvement this wind mill may be made to go of the wind, when wanted, & also stopped as easy, and regular as a water mill.

which splits the leather. Several pairs of leather and bone pins are fitted to it, so fitted into the
frame, so as to hold the leather in place while splitting. The ends of which are, in general, on
each square roller so as to prevent the leather from stretching. A pair of upper and lower
pins is fitted with proper leather straps to this roller. These nipples take hold of the leather &
by turning said central roller they haul it through and as it is split, it then is wound
round this roller. On one end of this central roller a contrate case is mounted two feet
in diameter is firmly fixed. This contrate wheel is turned by a pinion to which a handle
is fixed by which the whole machine is made to operate. Another roller is also placed on
the frame so as to keep the leather while splitting up close to the surface of the cylinder. The
roller under the edge of the knife and which forms the gauge is made of cast iron about five inch
in diameter and is accurately turned. The three rollers are made of hard wood. The sides
of New's leather as well as whale and other skins, may be split by this machine and
wet so as to make the skinning out of one.
